LIFT TRUCK

Arthur E. Williams, Jersey City, N. J., assignor
to Henry S. Germond, Bayonne, N. J.

Application March 21, 1936, Serial No. 70,024

4 Claims. (Cl. 254—10)

This invention relates to that class of trucks commonly called "lift-trucks" or elevating trucks which are used in lifting and transporting loads that are usually mounted on platforms or skids, 5 the truck being capable of being pushed under a skid and then raising the same on the elevating platform of the truck for transportation.

Such trucks usually include a wheeled main frame, an elevating platform mounted thereon 10 to move vertically upon being pulled horizontally, a handle for pulling the truck, an operative connection between the handle and the elevating platform for raising the latter and a latch for holding the elevating platform in elevated position.

One object of my invention is to provide a truck of this general character embodying novel and improved features of construction whereby the handle shall be permanently operatively connected to the elevating platform so that it shall be unnecessary to manually connect and disconnect the handle from the platform, as is now common in known trucks.

Another object is to provide in such a truck 25 a novel and improved combination of a latch for holding the elevating platform in its elevated position and a locking dog for holding the latch in locking position with respect to the elevating platform, said locking dog to be automatically thrown out of locking relation to the latch by and upon swinging of the handle into a position for starting elevation of the elevating platform, whereby the possibility of the platform accidentally descending in such a manner as to suddenly throw the handle upwardly is prevented, and the locking dog may be easily and quickly thrown out of locking relation to the latch at the proper moment and with a minimum of attention by the operator.

40 A further object is to provide a lift truck of the general character described embodying a novel and improved construction for varying the height of the elevating platform to accommodate load carrying skids or platforms which are disposed at different distances from the floor.

Other objects are to provide in such a lift truck a novel and improved hydraulic check for retarding descent of the elevating platform and to obtain other advantages and results as will be brought out by the following description.

Referring to the drawings in which corresponding and like parts are designated throughout the several views by the same reference characters—

55 Figure 1 is a side elevation of a lift truck

embodiment of my invention, portions being broken away and the elevating platform being shown in its lower or normal position.

Figure 2 is a top plan view of the truck.

Figure 3 is a front end elevational view thereof. 5

Figure 4 is an enlarged longitudinal vertical sectional view on the line 4—4 of Figure 2.

Figure 5 is a similar view showing the elevating platform in its uppermost position.

Figure 6 is a like view showing the manner of 10 throwing the locking dog out of locking relation to the latch.

Figure 7 is a transverse vertical sectional view on the line 7—7 of Figure 1.

Figure 8 is a fragmentary side elevation of the 15 rear end of the truck showing the adjustment of the elevating platform, and

Figure 9 is an enlarged fragmentary sectional elevational view of the hydraulic check.

Specifically describing the illustrated embodiment of the invention, the reference character A designates the main frame of the truck which is mounted at its rear end on wheels 1 journaled on an axle 2 extending transversely in the main frame. The front end of the frame includes a 25 bolster 3 on which is journaled on the longitudinal median line of the frame, a caster 4 whereby the truck may be guided upon lateral pulls on the forward end of the frame.

An elevating platform B is mounted on the 30 main frame A by a pair of parallel links 6 at the forward end of the frame and a similar pair of links 7 at the rear end of the frame. The forward links are pivotally connected to the main frame and platform on the respective pivot pins 35 8 and 9, while the rear links 7 have their ends pivotally mounted respectively on the rear axle 2 and a cross rod 10 the ends of which are journaled in adjustable brackets 11 which are secured to the sides of the elevating platform by bolts 40 12 as will hereinafter more fully be described. With this construction, a forward pull on the elevating platform will result in it being raised from the main frame.

For raising the elevating platform, I have 45 shown a transverse rod 13 at the forward end of the platform to which is pivotally connected a pair of lifting links 14, one at each side of the platform. The links have longitudinal slots 15 in which is slidable a cross bar 16 which connects 50 corresponding arms 17 of bell crank levers 18 which are pivoted intermediate their arms on a shaft 19 at the top of the bolster, one at each side of the main frame. The other arms of the bell cranks are connected by a U-shaped handle 20. 55

The parts are so related that when the elevating platform **B** is in its lowermost position as shown in Figures 1 and 4, and the handle **20** is in substantially a vertical plane, the cross bar **16** is in the upper ends of the slots **15** of the links **14** and forward swinging of the handle **20** will elevate the platform as shown in Figure 5, whereupon, the platform being held in elevated position by a latch about to be described, the handle may be freely swung about the shaft **19** without movement of the platform, the cross bar **16** riding in the slots **15**.

The elevating platform is held in its uppermost position by a latch **21** which is pivotally mounted intermediate its ends on the shaft **19** and has at one end a hook **22** to engage over the rod **13** at the forward end of the platform. The other end of the latch comprises a treadle **23** for disengaging the hook **22** from the rod **13**. A spring **24** normally influences the latch so as to bring the hook **22** in position to snap over the rod **13** when the elevating platform reaches its uppermost position, the hook end **22** of the latch having a projection **25** to facilitate riding of the hook over the rod **13**.

To prevent accidental disengagement of the latch from the rod **13** in such a manner as to allow the platform to suddenly descend under the weight thereon and cause possible injury to the operator by sudden upswing of the handle **20**, I have provided a locking dog **26** which is pivotally mounted at one end at **27** on a standard **28** at the forward end of the elevating platform, the dog overlying the rod **13** as shown in Figures 4 and 5. The dog is held in this position by action of gravity and is so spaced from the rod **13** that the hook **22** may swing the dog rearwardly and then snap over the rod **13** when the platform **B** reaches its uppermost position. The dog then swings by gravity into a position over the hook **22** and is so spaced from the hook as to prevent swinging of the hook upwardly sufficiently to disengage the hook from the rod **13**, as shown in Figure 5.

The dog **26** is automatically thrown out of such locking position as the handle **20** is raised, by engagement of the dog by the cross bar **16** which connects the bell cranks **18** as shown in Figure 6, whereupon the latch may be disconnected from the rod **13** and the platform may be released for descent. It will be noted however, that at this time the handle is in substantially its uppermost vertical position with the cross rod **16** at the inner ends of the slots **15** in the lifting links **14** so that the descent of the platform will not have any effect upon swinging of the handle. All danger to the operator is thereby eliminated. When the handle is again swung downwardly the dog will swing into its normal locking position by action of gravity as shown in Figure 4.

Another feature of the invention is an adjustable mounting of the elevating platform **B**. As shown, the forward parallel links **6** are connected to the standard **28**, and the side pieces **29** of the elevating platform are bolted at **30** to the standard. The standard has a plurality of vertically spaced openings **31** so that the side pieces **29** can be connected to the standard at different elevations.

The rear end of the elevating platform carries the brackets **11** which have two pairs of openings **31** spaced different distances from the point of journaling of the rod **10** in the brackets. Accordingly when the brackets are connected to the side pieces of the elevating platform with the

bolts **12** passing through one pair of openings **31**, the platform will be at one elevation as shown in Figure 1; while upon reversing of the brackets **11** and connecting them to the side pieces of the platform **B** with the bolts passing through the other set of openings **31**, the platform will be disposed at a higher elevation as shown in Figure 8.

Lift trucks of this general character usually include a hydraulic check for retarding descent of the elevating platform and my invention contemplates a novel and improved check. As shown in the drawings, the check includes a cylinder **32** pivotally mounted at one end **33** on the rear axle **2** and having a piston **34** reciprocable therein which has a piston rod **35** pivotally connected at **36** to the standard **28** on the elevating platform.

The piston comprises two plates **36** which are riveted together and clamp between them a cup packing washer **37** to engage the inner walls **20** of the cylinder and facing in the direction of movement of the piston as the platform descends. The piston has a limited sliding movement on the rod **35**, movement being limited in one direction by a collar **38** and being limited in the other direction by nuts **39**. The inner end of the piston rod has a longitudinal groove **40** leading beneath the nuts **39** and the piston **34** to the collar **38** and the collar has a packing washer **41** to be abutted by the piston. The cylinder is **30** filled with liquid such as oil, and when the platform **B** is elevated, the piston rod moves to the left of Figures 1 and 9 and the piston during the initial movement of the rod slides into engagement with the nuts **39** so as to permit the oil to **35** flow through the groove **40**. Some oil will also flow around the edges of the packing washer **37**. When the elevating platform descends, the rod **35** moves in the opposite direction and upon initial movement the piston **34** slides against the packing **40** washer **41** to close the groove **40**, and the packing washer **37** expands tightly against the cylinder wall to prevent the flow of oil past the piston. Descent of the elevating platform is thereby retarded, but to permit slow movement of the platform, the piston has a leak port **42** which allows the oil to flow slowly from one end of the cylinder to the other in such a manner as to allow descent of the platform but at a slow rate.

Obviously the truck may be moved from place to place by pulling on the handle **20**, lateral pulls causing the forward end of the truck to swing on the caster **4** to permit steering of the truck.

While I have shown and described the invention as embodied in certain details of construction it should be understood that this is primarily for the purpose of illustrating the principles of the invention and that the details of structure may be modified by those skilled in the art without departing from the spirit or scope of the claims.

Having thus described my invention, what I claim is:

- An elevating truck comprising a wheeled main frame, an elevating platform mounted on said main frame for movement vertically upon being pulled forwardly, a pair of links pivoted at one end on said platform, one at each side thereof and having an elongated slot, and a handle having a pair of rigidly connected bell cranks pivoted to rotate about a horizontal axis on, and one at each side of, said main frame, and a cross rod connecting corresponding arms of said bell cranks and slidably in said slots so that said platform can be elevated by swinging

of said handle downwardly in one direction and engagement of the outer ends of said slots by said cross rod, and after elevation of the platform said handle may be swung upwardly and 5 said cross rod may slide toward the other ends of said slots to permit the platform to descend with said links sliding idly over said cross rod without effecting movement of the handle, and means for releasably locking said platform in elevated position.

2. An elevating truck comprising a wheeled main frame, an elevating platform including side pieces and a standard connected to said side pieces at one end, a bracket secured to each side piece 15 adjacent the rear end thereof, a shaft journaled in said brackets, a pair of parallel lifting links pivotally connected at one end to said shaft and at their other ends to the main frame, a second pair of parallel links pivotally connected at one 20 end to said standard and at their other ends to said main frame, means adjustably mounting said brackets on said side pieces and means adjustably mounting the side pieces vertically on said standard to vary the height of the elevating 25 platform.

3. An elevating truck comprising a wheeled main frame, an elevating platform including side pieces and a standard connected to said side pieces at one end, a bracket secured to each side 30 piece adjacent the rear end thereof, a shaft journaled in said brackets, a pair of parallel lifting links pivotally connected at one end to said shaft and at their other ends to the main frame, a second pair of parallel links pivotally connected 35 at one end to said standard and at their other ends to said main frame, each side piece having a set of bolt openings and each bracket having a plurality of sets of bolt openings spaced different distances from the point of journaling of said 40 shaft in said brackets to selectively cooperate

with said sets of openings in the side pieces to receive bolts for connecting the brackets to the side pieces in different positions and vary the height of the platform, said standard having a plurality of sets of bolt holes at each side and 5 each side piece having a set of bolt holes to selectively cooperate with said sets of holes in the standard and receive bolts for connecting said side pieces to said standard at different heights.

4. An elevating truck comprising a wheeled main frame, an elevating platform mounted on said main frame for movement vertically upon being pulled forwardly, a pair of links each pivoted at one end on said platform at one side thereof and having an elongated slot adjacent 15 its other end, and a handle having a pair of rigidly connected bell cranks pivoted to rotate on a horizontal axis on said main frame and a cross rod connecting corresponding arms of said bell cranks and slideable in said slots in the links so 20 that said platform can be elevated by swinging of said handle downwardly in one direction and engagement of the outer ends of said slots by said cross rod, and after elevation of the platform said handle may be swung upwardly and 25 said cross rod may slide toward the other ends of said slots to permit the platform to descend without affecting movement of the handle, a latch on said main frame to engage a part on said platform for holding said platform in elevated position, a locking dog on said platform actuated by gravity into position to lock said latch in holding position when the platform is elevated, said dog being located on the platform so that when the platform is locked in elevated position 30 the dog is directly engaged by said cross rod of the handle as the handle is swung upwardly and reaches the position for beginning elevation of the platform.

ARTHUR E. WILLIAMS. 40
